(Cl. D22—3)

To all whom it may concern:

Be it known that we, William Selikoff and William B. McBride, respectively citizens of the United States, and both residing in Buffalo, in the county of Erie and State of New York, have invented a new, original, and ornamental Design for a Cheese Slicer or the like, of which the following is a specification, reference being had to the accompanying drawings, forming part thereof.

In these drawings:

Fig. 1 is a top plan view of a cheese slicer, embodying our new design.

Fig. 2 is a front elevational view thereof, the rear elevational view being substantially identical thereto.

Fig. 3 is an end elevational view thereof, the

opposite end elevational view being substantially identical thereto.

Fig. 4 is a bottom plan view thereof.

We claim:

The ornamental design for a cheese slicer or the like, as shown.

WILLIAM SELIKOFF.

WILLIAM B. McBRIDE.
